[57] **CLAIM**

The ornamental design for lighting fixture, as shown and described.

DESCRIPTION

FIG. 1 is a front perspective view of a lighting fixture showing my new design as embodied in a pendant lamp;
FIG. 2 is a side elevational view thereof;
FIG. 3 is a bottom plan view thereof;
FIG. 4 is a rear elevational view thereof;
FIG. 5 is a front perspective view of a second embodiment of my design as embodied in a ceiling lamp;
FIG. 6 is a side elevational view thereof;
FIG. 7 is a bottom plan view thereof;
FIG. 8 is a rear elevational view thereof;
FIG. 9 is a perspective view of a third embodiment of my new design as embodied on a wall lamp;
FIG. 10 is a side elevational view thereof;
FIG. 11 is a bottom plan view thereof;
FIG. 12 is a rear elevational view thereof;
FIG. 13 is a front perspective view of a fourth embodiment of my design as embodied in a pendant lamp;
FIG. 14 is a bottom plan view thereof;
FIG. 15 is a bottom plan view thereof;
FIG. 16 is a rear elevational view thereof;
FIG. 17 is a front perspective view of a fifth embodiment of my new design as embodied in a ceiling lamp;
FIG. 18 is a side elevational view thereof;
FIG. 19 is a bottom plan view thereof;
FIG. 20 is a rear elevational view thereof;
FIG. 21 is a front perspective view of a sixth embodiment of my design as embodied in a wall lamp;
FIG. 22 is a side elevational view thereof;
FIG. 23 is a bottom plan view thereof;
FIG. 24 is a rear elevational view thereof.
